UNITED STATES PATENT OFFICE.

CORNELIUS HAMLER, OF NEWTON, NEW JERSEY, ASSIGNOR TO ANDREW SHINER, OF SAME PLACE.

IMPROVEMENT IN SCYTHE-FASTENINGS.

Specification forming part of Letters Patent No. 117,623, dated August 1, 1871; antedated July 21, 1871.

To all whom it may concern:

Be it known that I, CORNELIUS HAMLER, of Newton, in the county of Sussex and State of New Jersey, have invented a new and useful Improvement in Fastening and Adjusting Scythes; and I do hereby declare that the following is a full, clear, and exact description thereof, which will enable others skilled in the art to make and use the same, reference being had to the accompanying drawing forming part of this specification, in which—

Figure 1 is a rear view of the lower end of a scythe-snath, to which the scythe is connected by my improved device. Fig. 2 is a detail face view of the part attached to the scythe, partly in section, through the line $x x$, Fig. 1. Fig. 3 is a face view of the part attached to the snath, partly in section, through the line $x x$, Fig. 1.

My invention has for its object to furnish an improved device for connecting a scythe to a scythe-snath which shall be simple in construction and easily adjusted so as to enable the scythe to be conveniently hung out or in, or moved so as to be parallel with the snath, for convenience of carriage; and it consists in the construction of the parts of the device, as hereinafter more fully described.

A represents an ordinary scythe-snath, to the under side of the lower end of which is securely attached a plate, B, having a circular projection, C, formed upon its middle part. The circular projection C has a set of teeth formed upon its face around

its outer edge, as shown in Fig. 3. D is a plate having a hole formed in it near its upper end to receive the toe of the shank of the scythe E. The other or lower end of the plate D is secured to the lower part of the scythe-shank by a bolt and nut, as shown in Figs. 1 and 2. Upon the middle part of the plate D is formed a circular projection, F, having a set of teeth formed around the outer edge of its face, as shown in Fig. 2. The teeth of the projections C and F should be fine, so that the scythe may be accurately adjusted or set out or in slightly, as required. This construction also enables the scythe to be adjusted to extend along the snath for convenience in carrying it. G is a bolt passing through the center of the plates D E and B C and through the lower part of the snath A, and secured in place by a nut, as shown in Fig. 1 and in dotted lines in Fig. 3, so that by loosening the nut upon the bolt G the scythe may be adjusted as desired.

Having thus described my invention, I claim as new and desire to secure by Letters Patent—

The plate B having circular ratcheted projection C, the apertured plate D having ratcheted projection E, and the bolt G, combined, as described, with the snath A and scythe E, for the purpose specified.

CORNELIUS HAMLER.
